Filed Mar. 24, 1969, Ser. No. 16,406

Term of patent 14 years

Int. Cl. D23—01

U.S. Cl. D67—4

FIG. 1 is a perspective view of a drinking fountain viewing the same from the front, showing my new design;

FIG. 2 is a bottom plan view of the fountain shown in FIG. 1;

FIG. 3 is a vertical sectional view of the fountain taken on the line 3—3 of FIG. 2;

FIG. 4 is a view similar to FIG. 1, but showing a modified design of the fountain.

I claim:

The ornamental design for a drinking fountain, substantially as shown and described.
